UNITED STATES PATENT OFFICE.

JOHN R. MCGIFFERT, OF DULUTH, MINNESOTA, ASSIGNOR TO CLYDE IRON WORKS, OF DULUTH, MINNESOTA, A CORPORATION OF MAINE.

LOG-SKIDDING MACHINE.

1,160,301.

Specification of Letters Patent.

Patented Nov. 16, 1915.

Application filed January 17, 1914. Serial No. 812,641.

To all whom it may concern:

Be it known that I, JOHN R. MCGIFFERT, a citizen of the United States, and a resident of Duluth, county of St. Louis, and State of Minnesota, have invented a new and useful Improvement in Log-Skidding Machines, of which the following is a specification, the principle of the invention being herein explained and the best mode in which I 10 have contemplated applying that principle, so as to distinguish it from other inventions.

The present invention relates to a new type of boom and an improved mounting for booms which are to be used for the purpose of lifting and transporting heavy loads.

The invention is particularly adapted to be used in connection with log skidding machines, one form of which is illustrated in the drawings to be hereinafter described, and 20 the particular feature of the invention to which attention is called is the flexible mounting for the boom, which absorbs all shocks and permits the guy lines which maintain the boom against lateral movement, 25 to be kept tight at all times.

To the accomplishment of these and related ends said invention then consists of the means hereinafter fully described and particularly pointed out in the claims.

30 The annexed drawings and the following description set forth in detail certain mechanism embodying the invention, such disclosed means constituting, however, but one of various mechanical forms in which the 35 principle of the invention may be used.

Figure 1 is a partial side elevation of a log skidding machine showing the attachment of my invention thereto; Fig. 2 is a plan view of the same, but omitting certain parts 40 of the boom; Fig. 3 is a section on the line 3-3 in Fig. 2; Fig. 4 is a section on the line 4-4 in Fig. 1; and Fig. 5 is a section on the line 5-5 in Fig. 1.

The general features of the log skidding 45 machine, are too well known to require detailed explanation in this connection, the machine comprising a frame or car 1 which may be moved over a suitable track 2, there being mounted upon the car suitable drums for 50 the purpose of controlling movement of the different cables which are required in the operation of the machine. At one end of the machine I pivotally mount about a substantially vertical axis a horizontal member

5 which extends on either side of its axis, the 55 ends of such member being engaged by resilient restraining means which will preferably take the form of a plurality of compression springs 6 as here illustrated for the purpose of normally maintaining such member 60 in a predetermined position. These restraining means are, however, adapted to permit the member to oscillate slightly about its axis under any abnormal rotative pressure. The precise mounting for the compression springs 6 is not important but I have 65 here shown them as being mounted horizontally against suitable backing plates 7 attached to the car frame.

The boom in the present machine is preferably of A-form, the two legs 8 in such boom being pivotally connected at their lower ends to the two extending ends 9 of the member 5 on the frame, such pivotal connection being about a horizontal axis. Mounted just back 75 of the springs 6 upon the frame is a second A-boom or frame 10 extending vertically upward and to the upper end or peak 11 of such frame is pivotally attached about a substantially vertical axis, which is substantially 80 aligned with the axis of the member 5, a single bar or member 12 which extends outwardly and is attached at its outer end to the peak 13 of the main boom. The legs of the boom and the outwardly extending member are 85 maintained in such rigid relation by means of other lugs or angle bars attached to the same at intervals along their length, thus providing a rigid construction although permitting the boom to oscillate very slightly 90 in a lateral direction and permitting also the rigid support or upper member to oscillate simultaneously therewith. The purpose of this resilient mounting for the boom will be seen from an inspection of the cables 95 which are supported at different points upon suitable sheaves from the boom.

The car is first moved to a suitable point by means of the car propelling means mounted on the car itself. The boom is then 100 braced against lateral movement by means of several guy wires or cables 14 operated by drums 16 upon the frame and extending in divergent directions on one side of the peak 13 of the boom. These guy wires 14 105 are usually attached to stumps or trees, and if any great pressure is put upon them they cut into the tree or stump and thus become

slightly slack. A considerable pressure will be put upon these guy wires since on the other side of the boom there extends a trolley cable 15 upon which a carriage 20 is mounted, the carriage bearing thereover a skidding line 17 which is operated by a drum 18 upon the frame as indicated. The skidding line 17 when attached to a log or other load, and when drawn in, exerts a great amount of pressure on the carriage 20 tending to move the same toward the boom, or if this is prevented (as it is), to move the carriage down, thus stretching the trolley cable and tending to move the boom to the right. If there is the slightest amount of slackness in the guy wires, the boom responds to the pressure in the trolley and slips to the right. It will be seen that the boom and support are practically a rigid structure which is so mounted that it may swing as a whole very slightly in a lateral direction about a substantially vertical axis.

The resilient restraining means which control the oscillation of the horizontal member on the car are provided to absorb any such slight oscillation of the boom and to prevent the same from passing its oscillation to the car itself. The compression springs are, of course, sufficiently rigid to maintain the boom in its normal position against any ordinary strain. The wear on the machine resulting from the usual shocks is thus entirely eliminated.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. The combination with a suitable support; of a boom oscillatorily mounted thereon about a vertical axis; and restraining means adapted to normally maintain said boom in a predetermined position but to permit oscillation of the same under abnormal lateral pressure in either direction.

2. The combination with a suitable support; of a boom oscillatorily mounted thereon about a vertical axis; and resilient restraining means adapted to normally maintain said boom in a predetermined position but to permit oscillation of the same under abnormal lateral pressure in either direction.

3. The combination with a suitable support; of a boom oscillatorily mounted thereon about a vertical axis; and a plurality of springs adapted to normally maintain said boom in a predetermined position but to permit oscillation of the same under abnormal lateral pressure in either direction.

4. The combination with a suitable sup-

port; of a member oscillatorily mounted on the same about a vertical axis; a boom attached to said member; and resilient restraining means engaging said member on either side of its axis and adapted to maintain said member in a predetermined position but to permit oscillation of the same under abnormal lateral pressure in either direction.

5. The combination with a suitable support; of a member oscillatorily mounted on the same about a vertical axis; an A-boom having its legs attached to the ends of said member, respectively; and resilient restraining means engaging said member on either side of its axis and adapted to maintain said member in a predetermined position but to permit oscillation of the same under abnormal lateral pressure in either direction.

6. The combination with a suitable support; of a member oscillatorily mounted on the same about a vertical axis; an A-boom having its legs attached to the ends of said member, respectively; and a plurality of springs engaging said member on either side of its axis and adapted to maintain said member in a predetermined position but to permit oscillation of the same under abnormal lateral pressure in either direction.

7. The combination with a suitable support; of a member oscillatorily mounted on the same about a vertical axis; an A-boom having its legs attached to the ends of said member, respectively; and a plurality of horizontally disposed, compression springs engaging said member on either side of its axis and adapted to maintain said member in a predetermined position but to permit oscillation of the same under abnormal lateral pressure in either direction.

8. The combination with a suitable support; of a boom pivotally mounted thereon about a vertical axis; resilient restraining means adapted to normally maintain said boom in a predetermined position but to permit oscillation of the same under abnormal lateral pressure; and a rigid supporting member for said boom, said member being pivotally mounted about a vertical axis.

9. The combination with a suitable support; a boom pivotally mounted thereon about a vertical axis; resilient restraining means adapted to normally maintain said boom in a predetermined position but to permit oscillation of the same under abnormal lateral pressure; and a supporting bar connected at one end to the peak of said boom and having its other end pivotally connected to said support about a vertical axis.

10. The combination with a suitable support; of an A-boom pivotally mounted thereon about a vertical axis; resilient restraining means adapted to normally maintain said boom in a predetermined position but to permit oscillation of the same under abnormal lateral pressure in either direction.

abnormal lateral pressure; an A-frame mounted upon said support; and a rigid member attached at its outer end to the peak of said boom, said member having its inner end pivotally attached to the peak of said A-frame.

11. The combination with a suitable support; of an A-boom pivotally mounted thereon about a vertical axis; an A-frame mounted upon said support; and a rigid member attached to the peak of said boom, said member being pivotally attached to the peak of said A-frame about an axis substantially alined with the axis of said A-boom.

12. The combination with a suitable support; of an A-boom pivotally mounted thereon about a vertical axis; an A-frame mounted upon said support; a rigid member attached to the peak of said boom, said member being pivotally attached to the peak of said A-frame about an axis substantially alined with the axis of said A-boom; and

means rigidly connecting said A-boom and said rigid member.

13. The combination with a suitable support; of an A-boom pivotally mounted thereon about a vertical axis; an A-frame mounted upon said support; a rigid member attached to the peak of said boom, said member being pivotally attached to the peak of said A-frame about an axis substantially alined with the axis of said A-boom; means rigidly connecting said A-boom and said rigid member; and resilient restraining means adapted to normally maintain said boom and said member in a predetermined position but to permit oscillation of the same under abnormal lateral pressure.

Signed by me, this 12th day of January, 1914.

JOHN R. McGIFFERT.
